United States Patent Office.

JAIRUS BROWN, OF PORTLAND, MICHIGAN, ASSIGNOR TO HIMSELF AND
THEODORE B. HUBBARD, OF SAME PLACE.

Letters Patent No. 77,353, dated April 28, 1868.

IMPROVEMENT IN REELS.

The Schedule referred to in these Letters Patent and making part of the same.

TO WHOM IT MAY CONCERN:

Be it known that I, JAIRUS BROWN, of Portland, in the county of Ionia, and State of Michigan, have invented a new and useful Improvement in a Swift and Reel; and I do declare that the following is a full and exact description thereof, reference being had to the accompanying drawings, and to the letters of reference marked thereon, and being a part of this specification.

Figure 1 represents my invention, when standing upright, and to be used as a swift.

Figure 2 represents the same, with the arms in another position, when used as a reel.

The same letters indicate like parts in each figure.

The nature of this invention consists in arranging a series of adjustable arms, so that the apparatus can be used either as a swift or reel, and when not in use, it can be folded up into a small compass, and laid away in any convenient place.

In order to do this, I construct a jaw, A, in the usual form, provided with set-screw B, for the purpose of attaching the apparatus to a proper table or shelf. The upper end of this jaw-frame is provided with a proper joint, C, to which is attached the bar D, and which will allow the bar to be moved from a horizontal to a perpendicular position. The lower part of this bar has a screw-thread, E, cut upon it, which, when the bar is horizontal, so that the apparatus can be used as a reel, meshes into the wheel F, to which are attached the spring G, and suitable mechanism to mark the knots of yarn or thread as it is reeled. H is a loose sleeve, fitting upon the square part of the bar D. This sleeve H is adjustable to any part of the square part of said bar, by means of the set-screw I. J is another loose sleeve, also fitting upon the bar D, and which is also adjustable upon the bar D by the set-screw K. The arms L are pivoted to proper ears upon the sleeve J, at their inner ends, and to the bars M at their outer ends. N are proper braces extending from the outer arms, L, to which they are pivoted to proper ears upon the sleeve H, to which they are also pivoted. These braces also act as levers to open or close the arms L.

What I claim as my invention, and desire to secure by Letters Patent, is—

The combination of the adjustable sleeves H and J, arms L, bars M, braces N, bar D, having a screw-thread, E, and being hinged at C with the holder A, wheel F, and spring G, all constructed and arranged substantially as and for the purposes described.

JAIRUS BROWN.
